UNITED STATES PATENT OFFICE

RUDOLPH F. STEHLIK, OF CHICAGO, ILLINOIS, ASSIGNOR TO RESERVE HOLDING COMPANY, OF KANSAS CITY, MISSOURI, A CORPORATION OF DELAWARE

TELEPHONE SYSTEM

Application filed August 27, 1927, Serial No. 215,793. Renewed April 9, 1930.

The present invention relates to telephone systems in general, but is concerned more particularly with multi-office telephone systems including both automatic and manual offices.

5 The broad general object of the invention is the production of new and improved arrangements for handling calls originating in automatic offices and intended for lines terminating in manual offices. More particularly, the invention is especially applicable to 10 systems employing call indicators in the manual offices which are set in response to impulses transmitted from an automatic office by a register sender.

15 One object of the invention is the production of suitable arrangements including pre-selecting finders for associating the register-sender equipment with trunk lines that handle calls to the manual office, whereby the 20 necessity for extra hunting time is eliminated and the loss of calls due to this source is prevented. In this respect, the present invention may be said to be an improvement on or a modification of the arrangement 25 shown in Patent No. 1,559,736, granted Nov. 3, 1925 to Bellamy et al.

A feature of the invention lies in the arrangement whereby an interoffice trunk line from an automatic office to a manual office is 30 not taken for use until all digits in the number to be transmitted to the manual office have been registered and the apparatus is ready to retransmit the number. By this arrangement, a material reduction in the holding 35 time of the trunk lines is effected, which results in a given number of trunk lines being able to carry a larger amount of traffic.

Another object of the invention is to provide means for eliminating any wait, after 40 a trunk line to a manual office has been seized, for registering equipment to be connected to the seized trunk line. This object is attained by providing finder switches of the preselecting type to connect the registers in the manual office to the trunk lines, two such registers being provided, and by rendering the trunk lines non-selectable in the automatic office until they have been preselected in the manual office. With this arrangement in use, the 45 switching equipment in the automatic office

passes over the non-preselected trunk lines and selects only a trunk line that has been preselected.

A further feature of the invention lies in the arrangement incidental to the preselecting arrangement whereby the cord circuits at the operator's position are preselected in regular rotation, with the result that the operator can locate the next cord to be used more readily than if the cords were taken for use 60 more or less promiscuously.

According to another feature of the invention, the two independently operable finders in the manual office, one for each register, are provided with separate test conductors and 65 associated arrangements so that either finder cannot preselect a trunk after it has been preselected by the other.

Another object of the invention is the production of new and improved arrangements 70 for transferring quickly a number from the automatic office to the registering equipment in the manual office without sacrificing reliability, and at the same time using simple circuit arrangements and standard equipment. This object is attained by providing 75 circuit arrangements such that two digits may be transmitted simultaneously, one over each talking conductor of the interoffice trunk line.

It is a further object of the invention to provide circuit arrangements such that the equivalent of full metallic impulse circuits is obtained. In order to accomplish this object, arrangements have been provided so that when two digits of equal length are transmitted, the impulsing circuit is thru the two conductors of the trunk line in series and independent of a ground connection except in the manual office, special holding arrangements 80 being provided for preventing the response of one of the receiving relays while the remaining portion of a long digit is being transmitted over one of the conductors in case the two digits to be transmitted simultaneously 85 are of unequal length.

There are a number of other objects and features of the invention, which are more or less incidental to the foregoing, being concerned more or less with the circuit details 100

involved carrying out the main objects of the invention. The various objects and features of the invention will be understood best from the following description in connection with the accompanying drawings comprising Figs. 1-7.

Referring now to the drawings, Figs. 1-6 are circuit diagrams showing so much of the equipment in a telephone system embodying the features of the invention as is necessary for the invention to be understood, and Fig. 7 is a layout drawing showing the way in which the sheets of drawings should be arranged in order to be understood best.

Figs. 1-3, taken together, show the trunking and switching equipment necessary to set up a connection from the automatic substation A to the manual substation B. Figs. 4 and 5 show the registering and sending equipment in the automatic office, and Fig. 6 shows the registering and call-indicating equipment in the manual office.

Fig. 1 shows the line switch LS individual to the line of substation A. The office selector OS, accessible to the line switch LS, has access, on one level, to a number of repeaters, such as R. The trunk lines with which the repeaters are associated are the trunk lines thru which the calls are extended from the automatic office to the manual office containing the equipment shown in Figs. 5 and 6. Fig. 1 shows also the finder F, which is of the preselecting type and is controlled from the equipment shown in Fig. 4. This finder associates the register sender such as that shown in Figs. 4 and 5 with the repeater R.

The trunk line extending from the repeater R, Fig. 1, terminates in the secondary switch SS, Fig. 2. This secondary switch operates at the proper time and selects a trunk line, such as the trunk line TL extending to the manual office.

Fig. 3 shows the cord circuit CC in which the inter-office trunk line TL terminates. The cord circuit CC ends in a plug P which may be inserted in the jack J to complete the connection to substation B.

As pointed out above, Figs. 4 and 5 taken together show a complete register sender. Specifically, Fig. 4 shows the control relays 401-406 and the input-control sequence switch SE. The sequence switch SE distributes the series of impulses to the operating magnets of the registers shown in Fig. 5 and brings about a switching operation after all the digits have been received. Fig. 5 shows, in addition to the registers, the sender S which retransmits impulses in accordance with the setting of the registers.

In addition to the equipment mentioned in connection with Fig. 4, the distributor is shown in the lower left-hand corner of the sheet. This distributor is common to a number of finders such as the finder F, Fig. 1,

and it is used mainly to reduce the number of relays necessary to be used individual to each of the finders.

Fig. 6 shows two register sets, Nos. 1 and 2, for controlling the display of numbers on the common lamp bank. Only one register set is shown in full. Each set is provided with a finder switch, as shown, to connect it with an idle cord circuit, such as the cord circuit CC, Fig. 3.

It may be pointed out at this time that the trunk lines such as the one comprising conductors 107-109, Fig. 1, extending to the repeaters such as R are normally made artificially busy and a trunk line is selectable only after it has been preselected by the finder such as F. In order for this arrangement to be used most advantageously, it is preferable that a separate group of finders be provided for each group of selectors such as the group including the selector OS. By way of example, it has been assumed that the selector OS is capable of taking twenty rotary steps and has access therefore to twenty trunks on any level. That being the case, the finder F has access to the same twenty trunks, the same being true of the other finders in the same group as the finder F. Other office selectors are formed into another group and twenty trunks are brought out from this group of office selectors. A separate group of finders is assigned to this second trunk group, a distributor such as the one shown in Fig. 4 being provided for this second finder group.

In this way, as many groups of trunks as are necessary may be provided to handle the traffic to any given manual office. It is assumed for convenience that the secondary switch SS, Fig. 2, (one of which is individual to each repeater) is arranged so that it may select any one of fifty trunks. It is assumed further that a group of fifty trunks is sufficiently large to handle the traffic from the automatic office in question to the manual office. If more trunks than fifty are needed, a switch capable of selecting more than fifty trunks may be provided instead of the secondary switch SS.

The invention having been described generally, a detailed description of the operation of the apparatus shown will now be given. For this purpose it will be assumed that the subscriber at substation A desires to converse with the subscriber at substation B. It will be assumed for convenience that the number of the subscriber at substation B is 5-2986, the digit 5 being the office designation, 2986 being the line number.

When the receiver is removed at substation A, the line switch LS responds to the closure of a circuit over the line of substation A and selects an idle office selector (selector OS, for example) in the usual manner by advancing its wipers 101-103 into engagement with an idle trunk line leading to such

office selector. When the subscriber at substation A dials the office digit 5 in the desired number, the office selector OS raises its wipers 104—106 opposite the fifth level of bank contacts and rotates them in search of an idle 5 trunk line.

At this point the description of the progress of the call will be temporarily dropped and the description of the manner in which the repeater R is preselected and made available for use will be taken up. Referring to the distributor shown in Fig. 4, and assuming that the bank contacts on which its test wiper 420 is standing has been grounded due to the completion of the operation of the associated finder, a circuit is closed thru wiper 420 for relay 422. When this happens, relay 422 operates and opens the circuit of relay 421, whereupon relay 421 falls back and among other things connects magnet 423 to test wiper 420. Magnet 423 being self-interrupting, operates in a buzzer-like manner to advance the wipers 417—420 step by step until test wiper 420 finds an ungrounded 20 test contact, for example the one associated with the register set shown. When this occurs, stepping magnet 423 ceases to operate, and relay 422 falls back and closes a circuit for relay 421. Relay 421 operates and disconnects stepping magnet 423. At its inner upper armature, relay 421 places ground on conductor 419, thereby closing a circuit thru test relay 401 and the operating magnet 120 of the finder F, Fig. 1, in series. At the same 30 time, relay 421, at its lower armature, connects wiper 417 to wiper 418 thereby connecting the junction of test relay 401 and stepping magnet 120 as represented by wiper 417, to the test wiper 121 of the finder F, as represented by wiper 418. If the repeater on which the finder F is standing is idle, the connecting up of test wiper 121 is without any particular effect and test relay 401, Fig. 4, operates right away. However, if the repeater 40 on which the finder is standing is busy or has been preselected by another finder, the test wiper 121 of the finder F is encountering a ground potential on the bank contact on which it is standing, thereby shunting test relay 401, Fig. 4, and preventing its energization. The ground potential on test wiper 121 is available for operating the stepping magnet 120 in the usual buzzer-like manner. Due to the action of operating magnet 120 the wipers 50 121—124 are advanced step by step until test wiper 121 encounters an ungrounded contact. Assuming that the first ungrounded contact is encountered by test wiper 121 when the wipers land on the set of bank contacts associated with the repeater R, the operation of test relay 401 in series with magnet 120, when this contact set is reached, results in the seizure of the repeater R. It may be pointed out that magnet 120 does not operate in series with test relay 401. Upon operating, relay 401 pre-

70 pares the incoming impulse circuit at its upper armature; prepares the outgoing impulse circuit at its two middle upper armatures; opens the test circuit at its inner upper armature and grounds the test wiper by connecting the said test wiper to its own upper terminal; at its lower armature, it grounds the test conductor in the bank of test wiper 420 of the distributor; and at its lower armature it removes ground from the release conductor 411 and applies ground to the interrupter-start conductor 414.

75 In the repeater R, as a result of the grounding of the test wiper 121 of the finder F by the inner upper armature of test relay 401, Fig. 4, relay 114 operates thru the middle lower armature of relay 115 and places ground on release trunk conductor 118, thereby closing a locking circuit for itself and supplying ground thru test wiper 121 to hold test relay 401, Fig. 4, operated after the distributor has been advanced. As a further result of the operation of relay 114, ground is removed from release trunk conductor 108 of the repeater R, thereby rendering the repeater R 80 selectable to the office selector OS and the others having access to it.

85 In the distributor, Fig. 4, when relay 422 operates as a result of the closure of its circuit by test relay 401 thru wiper 420, it opens the circuit of the associated slow acting relay 421 with the result that relay 421 falls back after a slight interval and opens the connection to wipers 417—419, at the same time connecting up operating magnet 423. Magnet 423 operates in the usual buzzer like manner to advance the distributor to another idle finder, whereupon the distributor stops and starts said finder in the manner above described.

90 105 As a result of the grounding of the interrupter start conductor 414 at the lower armature of test relay 401, impulse relay 505, Fig. 5, commences to operate and restore under the control of the interrupter I. It will be noted, however, that the operating magnet 504 of the sender S does not respond at this time owing to the fact that conductor 413 is not yet grounded.

110 115 Returning now to the description of the progress of the call, it will be assumed that the office selector OS seizes the preselected trunk line comprising conductors 107—109 leading to the repeater R when it rotates, after having been operated to the fifth level as hertofore described. When the repeater R is seized, line relay 111 operates thru contacts of the electro-polarized relay 110, over conductors 107 and 109, and over the calling line, and closes a circuit at its inner armature for release relay 112, at the same time opening at its lower armature a point in the impulse circuit to be subsequently traced and preparing a circuit for switching relay 115. Release relay 112 operates and places a multiple ground 120 125 130 135

connection on release trunk conductor 118 at its lower armature; prepares the impulse circuit at its inner lower armature; and at its upper armature places a ground potential on release trunk conductor 108 so as to cause the trunk to test busy to the other selectors having access to it and so as to provide a holding circuit for the selector OS and the line switch LS.

- 10 When the subscriber at substation A dials the thousands digit 2 in the desired number, line relay 111 falls back twice, momentarily. Each time it falls back, line relay 111 grounds the impulse conductor 125 thru contacts of release relay 112. Each time conductor 125 is grounded a circuit is closed thru wiper 124 of the finder F, upper armature of relay 401, Fig. 4, series relay 403 and the upper wiper of the sequence switch SE, in its first position, 15 for the operating magnet of the thousands register, Fig. 5. The operating magnet of the thousands register responds to these two impulses and advances the associated wiper two steps. The slow acting series relay 113, Fig. 1, is energized throughout the series of 20 impulses from the impulse conductor 125, but its operation is of no particular utility at this time.

25 Series relay 403, Fig. 4, operates in response to the first impulse delivered to the operating magnet of the thousands register, and, being slow acting, remains operated throughout the digit. Upon operating, relay 403 closes a circuit for the auxiliary slow- 30 acting relay 404, whereupon relay 404 operates and prepares a circuit for the operating magnet of the sequence switch SE.

35 When series relay 403 falls back at the end of the digit, it opens the circuit of auxiliary relay 404, and relay 404 falls back after a slight interval. During the time required for relay 404 to fall back after its circuit is opened a circuit is closed for the operating magnet of the sequence switch SE thru contacts of relays 403 and 404. The sequence switch SE, therefore, advances its wipers one step, shifting the impulse conductor from the operating magnet of the thousands register to the operating magnet on the hundreds register.

45 When the hundreds digit 9 is dialled, the operating magnet of the hundreds register responds by advancing the associated wipers step-by-step to the ninth bank contact; the operating magnet of the tens register responds to the tens digit 8 and sets the associated wiper; and the operating magnet of the units register responds to the units digit 6 and sets the associated wiper on the sixth bank contact. It will be understood of course that this progressive operation is brought about by the above described advance of the sequence switch SE at the end of each digit.

50 When the wipers of the sequence switch

SE advance onto the fifth bank-contact set at the end of the units digit, ground is encountered by the lower wiper of the sequence switch while the auxiliary relay 404 is still energized, closing a circuit thru contacts of relay 404, contacts of relay 401; wiper 123 of the finder F, upper contacts of relay 115 of the repeater R, conductor 117, and contacts of switching relay 202 of the secondary switch SS, for line relay 201. Line relay 55 201 responds and locks itself to the grounded release trunk conductor 118, grounded at this time at the lower contacts of release relay 112 of the repeater R. A moment later, the auxiliary relay 404 falls back and opens the initial circuit of the line relay of the secondary switch SS, leaving this relay locked to conductor 118.

As a result of the operation of the line relay of the secondary switch SS, a circuit is closed 55 at the inner lower contacts of the relay for switching relay 202 and operating magnet 203 in series. At the lower contacts of relay 202, test wiper 205 is connected to the junction of the associated switching relay and operating magnet. The result is that the operating magnet operates thru the test wiper and the switching relay 202 is maintained short circuited until wiper 205 is advanced to an ungrounded bank contact. 95

At this point the description of the call will again be momentarily halted while a description is given of the manner in which the registers in the manual office operate to preselect and render available the interoffice 103 trunks.

Referring now to Fig. 6, it will be noted that two registers are provided, register No. 1 and register No. 2. Register No. 1 is shown in full and it has associated therewith a finder having wipers 601-606. Assuming now that the finder is advanced in a manner to be subsequently explained from the bank contact set on which it is standing to the set associated with line TL, the said trunk 110 line TL is seized upon the operation of test relay 608 when the wipers 601-605 come to rest on the contacts in the trunk line. Relay 608 energizes through the lower contacts of relay 609 and through the operating magnet. 115 At its lower contacts relay 608 connects line relays 610 and 611 to the corresponding wipers 602 and 601; at its inner upper armature it disconnects the auxiliary test wiper 606; and at its inner lower armature it locks 120 itself energized independent of the inner lower armature of relay 612.

As a result of the line relays 610 and 611 being connected up at the contacts of relay 608, relay 212, Fig. 2, energizes thru wipers 601 and 602, conductors 321 and 322, contacts of relay 301, conductors 212 and 213, and contacts of relay 210. The line relays 611, 610 and 611, are not operated at this time owing 125 to the relatively high resistance of relay 211. 130

When relay 211 operates it disconnects ground from test conductor 208 and prepares a circuit for relay 210.

Returning now to the description of the progress of the connection, it will be assumed that the trunk line TL is the first available one found when the secondary switch SS operates in search of an available trunk line. That being the case, wipers 204—206 stop in engagement with the contacts to which conductors 207—209 are connected. The switching relay 202 operates in the usual manner when this trunk line is reached, extending the conductors 117 and 119 to the corresponding conductors 207 and 209. At its inner lower armature, relay 202 opens a point in the test circuit and places ground on test wiper 205, whereupon relay 210 operates over conductor 208 and contacts of relays 208—210 and locks itself to the said conductor. At its upper and lower armatures, relay 210 disconnects conductors 212 and 213 from relay 211 and connects them to conductors 207 and 209. Relay 211 now falls back and prepares to ground conductor 208 again.

The conductors 212 and 213 to which the line relays 611 and 610, Fig. 6, are connected are now extended thru conductors 207 and 209, wipers 204 and 206, contacts of relay 202, conductors 117 and 119, resting contacts of relay 115, wipers 122 and 123, contacts of relay 401, Fig. 4, contacts of relay 404, and contacts of relay 406 to the start-control relay 405. Relay 405 operates in series with the line relays of register No. 1, Fig. 6, but the said line relays do not operate due to the relatively high resistance of relay 405. Relay 405 closes a circuit for start relay 406, whereupon relay 406 operates and locks itself thru contacts of the switch-thru relay 402. Relay 406 also disconnects the negative and positive trunk-conductor extensions from the start-control relay 405 and extends them over conductors 415 and 416 to the closed loop including contacts of the sending relays 506 and 508. When this takes place, relays 610 and 611, Fig. 6, energize in series and each closes a circuit for release relay 612. Release relay 612 operates and prepares circuits for the operating magnets of the thousands and tens registers, respectively.

As a further result of the operation of start relay 406, Fig. 4, a multiple ground connection is made at its lower contacts to the test conductor extending to a contact in the bank of wiper 420 of the distributor; a multiple connection is made to the interrupter start conductor 414 at another lower armature of relay 406; and, at still another lower armature of relay 406, ground is placed on conductor 413 thru contacts of relay 402, whereupon the operating magnet 504 of the sender S commences to energize and deenergize under the control of the impulse relay 505, which relay it will be remembered is

operating under the control of the interrupter I from the grounded conductor 414. Upon each energization of the operating magnet 504 the usual pawl and ratchet arrangement (not shown) operates preparatory to advancing the wipers upon each deenergization of the magnet. When the operating magnet deenergizes the first time, as it does upon the next energization of impulse relay 505, wiper 501 encounters its second bank contact and thereby grounds conductor 510. As a result, each succeeding deenergization of relay 505 results in the closure of a circuit for sending relays 506 and 508 at the same time that a circuit is closed for the operating magnet 504. It will be noted that the circuit of sending relay 506 includes the upper winding and upper contacts of stop relay 507 and that the circuit of sending relay 508 includes the upper contacts and the upper winding of stop relay 509. The marginally adjusted stop relays do not operate in series with the sending relays.

According to the previous assumption, the thousands digit is the digit 2 and the tens digit is the digit 8. As a result the second contact in the bank of the thousands register is grounded and the eighth contact in the bank of the tens register is grounded. There is therefore no interference by the registers with the operation of the sending relays until two steps of the sending switch have been completed following the first step when the sending relays 506 and 508 start to operate. Each time the sending relays both operate, conductors 415 and 416 are both disconnected and left open, whereupon both line relays 610 and 611, Fig. 6, fall back. Then when sending relays 506 and 508 restore upon the energization of impulse relay 505, when the advance of the wipers 501—503 takes place, the line relays 610 and 611, Fig. 6, are connected in series again and they again operate. This operation is repeated upon the following step of the wipers of the sender, sending the second impulse to both line relays.

When the second impulse to the line relays is terminated, the wipers 501—503 land upon the fourth set of bank contacts, whereupon the ground potential placed on the second contact in its bank by the wiper of the thousands register is encountered by wiper 502, whereupon the sending relay 506 is deprived of battery potential and a stop relay 507 is energized thru its upper winding. Relay 507 locks itself to the grounded conductor 510 and disconnects sending relay 506. The result is that sending relay 506 remains normal during further advance of the sender S and the sending relay 508 operates alone.

Each time relay 508 operates alone, it grounds the negative conductor 516 thru the resistance R and thru contacts of sending relay 506 so as to hold the negative line relay 611, Fig. 6, operated, and it disconnects the

positive conductor 416, thereby deenergizing the positive line relay 610, Fig. 6. Each time sending relay 508 restores it connects the two line relays in series again, whereupon relay 610 reoperates. In this way, the two relays are energized in series over a metallic loop as before, but a high resistance holding circuit is maintained for one of them while the impulses are being delivered to the other. Therefore, the good effects of a loop impulsing circuit are retained while effective impulses are actually transmitted over only one conductor.

At the end of the eighth impulse transmitted to the positive line relay 611, Fig. 6, wiper 503 encounters the bank contact connected with the one grounded by the tens register in its eighth position, closing a circuit for the upper winding of stop relay 509. When this circuit is closed sending relay 508 is short circuited immediately so as to prevent further operation of relay 508, and stop relay 509 operates, locking itself to conductor 510 at its lower armature and disconnecting relay 508 at its upper armature.

The wipers of the sender S continue to advance and nothing more happens until wiper 501 passes off the eleventh bank contact and engages the disconnected twelfth contact. When this occurs, conductor 510 is ungrounded and relays 507 and 509 fall back and again connect up sending relays 506 and 508. Relays 506 and 508 cannot respond during the next two steps of the sender on account of the absence of a ground potential on conductor 510. This interval is provided in order to afford a spacing between series of impulses so as to allow the slow acting change-over relays in the registers in the manual office to fall back and perform change-over operations in a manner to be pointed out subsequently.

When the wipers 501—503 of the sender S arrive on the fourteenth contact set, wiper 501 grounds conductor 510 again. As a result, the sending relays 506 and 508 are operated again upon each succeeding deenergization of impulse relay 505, sending impulses over both conductors 415 and 416 to the line relays 611 and 610, Fig. 6. The sending operation continues uninterruptedly until wiper 503 encounters a contact grounded by the wiper of the units register after the sixth units impulses have been transmitted by sending relay 508. When this grounded contact is encountered, stop relay 509 operates and locks itself to the grounded conductor 510, at the same time disconnecting sending relay 508. As a result, relay 508 ceases to operate and the negative sending relay 506 continues to operate until the digit 9 has been transmitted over the negative conductor 415, whereupon stop relay 507 is energized thru wiper 502 of the sender and the wiper of the hundreds register in

series. When this occurs relay 507 locks itself to conductor 510 and disconnects relay 506.

The advance of the wipers of the sender continues until wiper 501 passes off the 24th bank contact and lands on the 25th bank contact. At this time conductor 510 is ungrounded and relays 507 and 509 fall back. When the 25th bank contact is grounded by wiper 501, a ground potential is extended over conductor 412 to the switch-thru relay 402, Fig. 4. Relay 402 operates and at its lower armature disconnects the operating conductor of the sender from ground through contacts of the start relay 406 and connects it instead to the grounded conductor 412. As a result, the operating magnet 504 derives current from conductor 412 thru the 25th bank contact of wiper 501 and advances the wipers another step into the normal position shown in the drawings. When this occurs the circuit of switch-thru relay 402 is opened, but this relay being slow acting, remains operated for an interval. As a further result of its operation, switch-thru relay 402 at its middle lower armature unlocks start relay 406 and places a multiple ground on the interrupter start conductor 414 so as to maintain the impulsing operation of relay 505 for the time being. Switch-thru relay 402 also places a ground on the impulse conductor extending to the impulse wiper 124 of the finder F, with a result to be subsequently mentioned. Relay 402 also opens the circuit of test relay 401, whereupon relay 401 falls back and replaces the ground potential on release conductor 411, thereby operating the release magnet 408 of the sequence switch SE thru the associated off-normal contacts, and operating the release magnets of the thousands, hundreds, tens and units registers, respectively, Fig. 5. By the operation of these release magnets the sequence switch and the registers are restored to their normal position and the release magnet circuits are opened by the respective off-normal contacts. After an interval, switch thru relay 402 falls back and removes ground from the impulse wiper 124 of the finder F at its upper armature, and it removes ground from impulse conductor 414 at its middle lower armature, whereupon the impulse relay 505, Fig. 5, ceases to operate and start relay 406 falls back and ungrounds the conductor extending to the bank of test wiper 420 of the distributor. The register sender is now selectable by the distributor and may be taken for use to handle another call.

Responsive to the placing of ground on the impulse wiper 124 of the finder F, as mentioned above, a circuit is closed thru contacts of release relay 112 and the lower armature, operated, of line relay 111 for the switching relay 115 of the repeater R. Relay 113 is op-

erated at this time, but its operation is merely incidental. Relay 115, at its middle lower armature disconnects relay 114, as it is no longer necessary to maintain this relay energized; it locks itself to the grounded conductor 118 and opens its initial circuit at its inner lower armature; and at its upper and lower armatures it disconnects the trunk conductors 117 and 119 from the bank contacts of the finder F and connects them instead to the talking conductors associated with the condensers above and below the electro-polarized relay 110. At the same time, a bridge is closed at the upper and lower armatures of relay 115 across conductors 117 and 119 including the lower winding of the electro-polarized relay 110 and impedance 126. When this bridge is closed, the line relays 610 and 611, Fig. 6, which have been restored following the deenergization of test relay 401, Fig. 4, reoperate, but the electropolarized relay 110 is not operated due to the contrary direction of the current flow in its lower winding.

Considering now the receipt, by the register No. 1, Fig. 6, of the transmitted impulses, each time the negative line relay 611 falls back in response to one of the two interruptions produced in its circuit representative of the thousands digit 2 it closes a circuit for the operating magnet of the associated thousands register, the circuit at the time of its first closure including the armature of relay 611, normal, inner upper armature of release relay 612, operated, normally-closed off-normal contacts of the thousands register, and the series relay 614. By the operation of the operating magnet, the wiper of the thousands register is advanced onto the second associated bank contact, thereby preparing a circuit for the No. 2 thousands lamp. Series relay 614 operates and remains operated throughout the digit, being slow acting. Relay 614 prepares a new impulsive circuit which becomes effective upon the shifting of the associated off normal contacts.

At the end of the thousands digit 2, series relay 614 restores and shifts the associated operating circuit from the operating magnet of the thousands register to the operating magnet of the hundreds register.

When relay 611 responds to the hundreds digit 9, nine impulses of current are delivered thru the off normal contacts of the thousands register TH and thru the contacts of series relay 614 to the operating magnet of the hundreds register through the associated series relay. The series relay of the hundreds register operates in response to the first series of impulses and remains operated throughout the digit. At its inner armature, the series relay of the hundreds register shunts the associated off-normal contacts so as to maintain its circuit intact thru the operating magnet until the end of the digit. At the end

of the digit, the off normal contacts having shifted, the series relay of the hundreds register falls back and opens the operating circuit so that any further operation of the negative relay 611 will not produce a response of the operating magnet. 70

When the positive relay 610 responds to the tens digit 8, which it does while the negative line relay is responding to the thousands digit, eight impulses of current are delivered to the operating magnet of the tens register over a circuit path similar to the one over which the impulses are transmitted to the operating magnet of the thousands register. This circuit path includes the resting contacts of relay 610 and operated contacts of release relay 612. By the combined action of the off normal contacts of the tens register and of the associated series relay, the impulse circuit is transferred from the tens register to the units register at the end of the tens digit. 75

When the units digit 6 is delivered coincident with the delivery of the hundreds digit 9, six impulses of current are delivered thru the series relay to the operating magnet of the units register, with the result that the wiper of the unit register is set on the sixth bank contact. By the joint action of the series relay of the units register and of the associated off-normal contacts the operating circuit is maintained intact until the end of the units digit, whereupon it is opened by the series relay. 80

With the hundreds register and the units register both in an operated condition with their off-normal contacts closed and with both of their series relays deenergized, a circuit for the display relay 613 exists, being established by whichever series relay falls back last. This circuit includes the off-normal contacts and series relay contacts of the hundreds and units registers, lower contacts of relay 612, and contacts of the display relay 613' of the register No. 2 and the display relay 613. When this circuit is closed, display relay 613 operates and opens a point in the circuit of display relay 613'. This interlocking arrangement between the two display relays is necessary to prevent a double display. The result of this arrangement is that if two displays are ready at the same time the first display relay to operate prevents the operation of the other until the first number has been disposed of and the successful display relay has fallen back. Upon the closure of the circuit thru display relay 613, this relay operates and grounds the wipers of the registers at its lower armatures, thereby causing the lamps on which the wipers of the registers are standing to become lighted and display the number 2986. 85

In order that the operator may know which cord circuit to use to complete the connection, a circuit is closed at the upper armature of 130

display relay 613 and thru wiper 604 and conductor 324 for the assign relay 305 of the cord circuit CC on which the wipers of the finder associated with register No. 1 are standing. Assign relay 305 operates and prepares a busy-back circuit at its lower armature, and it lights the assign lamp 308 at its upper armature.

Upon noting the lighted condition of the assign lamp 308, the operator picks up the plug P of the cord circuit CC and makes the usual tip busy test on the sleeve of the jack J. Assuming first that the jack J tests busy, the operator hears the busy click over the tip of the plug and thru her test circuit. The operator then merely replaces the plug in its normal position and operates the busy key 310, common to her position. At this time, only one assign relay, the assign relay 305, can be operated. As a result, relay 301 operates through contacts of relay 305 and switches the conductors 212 and 213 from in connection with conductors 321 and 322 and extends them instead to the left-hand repeating-coil windings. As a result line relay 302 operates and closes a multiple circuit for relay 301. At the same time, relay 301 places ground on conductor 323 so as to cause a further advance of the finder associated with register No. 1 in a manner to be hereinafter explained. Relay 302 also connects the busy-tone lead to the upper right-hand repeating-coil terminal thru the associated small condenser and contacts of sleeve relay 307. This busy tone is heard by the calling subscriber who replaces his receiver and brings about the release of the connection in a manner to be subsequently described.

Assuming now that the jack J tests idle, the operator inserts the plug P therein, whereupon sleeve relay 307 energizes over the sleeve of the plug and jack and thru the usual cut-off relay of the called line. At its inner upper armature, relay 307 opens a point in the busy tone circuit and it closes momentarily a circuit for the disconnect lamp 309 at its inner lower armature. Relay 307 also disconnects the tip conductor from the operator's test circuit and connects the tip conductors to ground through the upper right-hand repeating-coil winding and contacts of relay 304, and connects the ring conductor to the ringing circuit thru contacts of the ring-cut-off relay 306. Ringing current from the ringing interrupter is now sent out thru the lower winding of the ring-cut-off relay and thru the ring conductor to the called substation, returning to ground over the tip conductor. Since the upper right-hand repeating coil winding is included in the return path of the ringing current, a ringing tone is induced in the left-hand windings and is heard by the calling subscriber.

As a result of the closure of the circuit of relay 301, the conductors 212 and 213 are

shifted into connection with the left-hand repeating-coil windings, and line relay 302 operates and opens the circuit of the disconnect lamp 309 before the said lamp has had time to become lighted. Relay 302 also closes a multiple circuit for relay 301 so that it is now maintained operated from two sources.

As a further result of the operation of relay 301, conductor 323 is grounded, whereupon the operating magnet of the finder associated with register No. 1 is operated thru wiper 603, and test relay 608, being short circuited restores. Relays 610 and 611, Fig. 6, fall back as a result of the switching over of conductors 212 and 213 by relay 301, Fig. 3. Test relay 608 opens a point in its locking circuit, and, therefore, it cannot again reoperate, regardless of how far the wipers 601—606 advance until release relay 612 falls back responsive to the deenergization of relays 610 and 611. When relay 612 falls back, it connects up relay 608 again at its lower armature, and closes at its inner upper armature a circuit through the low-resistance lower winding of relay 609, including the upper armature of relay 611, for the release magnets of the register. This circuit includes the off normal contacts of the several registers. As a result of the closure of this circuit the registers are restored to normal position in the usual manner. As a further result of the deenergization of relay 612 the circuit of the display lamp 613 is opened immediately so that this relay falls back and extinguishes the lighted lamps and closes a point in the circuit of display relay 613' of the register No. 2. Since the circuit of the release magnets includes the lower winding of the guard relay 609, relay 609 operates when the release magnet circuit is closed and it again disconnects test relay 608 so as to prevent it from energizing during the releasing operation. Relay 609 also disconnects the test wiper 603 from the test circuit so as to prevent operation of the finder while the registers are releasing.

When the releasing operation is completed and all of the off normal contacts have opened, relay 609 falls back and permits the associated finder to preselect another trunk line.

Returning now to the established connection, when the called subscriber responds to the ringing of his bell by the ringing current sent out thru the plug P of the cord circuit CC, ring-cut-off relay 306, which relay does not respond to the ringing current due to the condenser included in series with the ringer at the called substation, responds to the flow of current from the exchange battery thru the ringing interrupter and over the called line. Upon responding, relay 306 removes the shunt from around its upper winding, thereby locking itself energized in series with sleeve relay 307; and at its upper and lower

armature it opens the ringing circuit and completes the talking circuit.

The battery-feed relay 304 now operates over the called line and removes the shunt from around its upper winding, at the same time closing a circuit for the reversing relay 303. Relay 303 reverses the connection between the windings of line relay 302 and the inner left hand repeating coil terminals, thereby reversing the current flow over the trunk line TL. Responsive to this reversal, the electro-polarized relay 110 in the repeater R, Fig. 1, operates and makes a similar reversal as regards the connection between conductors 107 and 109 and the windings of line relay 111. This latter reversal may be used whenever desired for the operation of meters or the like, or for giving supervision when the call is from an operator's switchboard at a private branch exchange, or for any other desired purpose.

The two subscribers may now converse with each other in the usual manner.

When the conversation is terminated, the two subscribers replace their receivers.

When the receiver is replaced at the substation B, battery-feed relay 304 falls back whereupon relay 303 is restored and reverses the connection between line relay 302 and the repeating coil windings back to normal. When this occurs, the electro-polarized relay 110, Fig. 1, restores and reverses the associated connections to normal.

When the receiver is replaced at substation A, line relay 111 of the repeater R falls back and opens the circuit of release relay 112, at the same time closing at its lower contacts a circuit thru contacts of relay 112 for relay 113. Relay 113 responds and opens a point in the guarding circuit of the repeater so as to enable the line switch LS and the office selector OS to release. A moment later, release relay 112 falls back and removes ground at its lower armature from release trunk conductor 118; opens the circuit of the slow acting relay 113 at its inner lower armature; and at its upper armature it removes ground from conductor 108 and prepares a circuit for replacing ground on conductor 108 when relay 113 falls back. When the ground potential is removed from conductor 108 the line switch LS and the office selector OS both release in the usual manner. A moment later relay 113 falls back and replaces the ground potential on conductor 108 so as to guard the repeater R from seizure by an office selector such as OS until the repeater R has been again pre-selected by a finder such as F. This preselection is now possible owing to the fact that the ground potential has been removed from release trunk conductor 118, a branch of which forms the test conductor in the bank of test wiper 121 of the finder F.

Responsive to the removal of the ground potential from release trunk conductor 118

by release relay 112 of the repeater R, line relay 201 of the secondary switch SS falls back and opens a further point in its locking circuit at its upper armature; it opens a further point in the test circuit of the line switch at its lower armature; and at its inner lower armature it opens the circuit of switching relay 202, whereupon relay 202 falls back, restoring the circuit conditions of the switch to normal. As a result of the disconnection of the ground potential from test wiper 205 by the switching relay 202, relay 210 of the trunk circuit TC, which has been energized previously over release trunk conductor 208, falls back and opens the circuit of the slow-acting relay 211 at its inner lower armature; closes a temporary guarding circuit through contacts controlled by its inner lower armature and the upper armature, operated, of relay 211; and at its upper and lower armatures it reconnects the high resistance relay 212 across the conductors of the trunk line TL. Relay 212 now operates and closes a locking circuit for the slow-acting relay 211 before the said relay has had time to fall back. Relay 211, therefore maintains the temporary guarding circuit closed as long as relay 212 remains operated.

Regarding the bringing in of the disconnect signal at the cord circuit CC, it may be pointed out that switching relay 115 of the repeater R, Fig. 1, falls back when the ground potential is removed from conductor 118 and it removes the bridge from across conductors 117 and 119, whereupon the line relay 302 of the cord circuit CC, Fig. 3, falls back and lights the disconnect lamp 309 thru contacts of sleeve relay 307. Due to the high resistance of relay 212, line relay 302 remains non-operated when relay 212 reoperates over the trunk line TL in series with line relay 302, as above pointed out.

When the operator notes the lighted condition of the disconnect lamp 309 and removes the plug P from the jack J, relays 306 and 307 fall back. Relay 307 opens the circuit of the disconnect lamp 309 and it also opens the circuit of relay 301, whereupon relay 301 falls back and disconnects the ground potential from test conductor 323 so as to render the cord circuit selectable to the associated finders. Relay 301 also disconnects the conductors 212 and 213 from the associated repeating coil windings. When this occurs, relay 212 in the trunk circuit TC, Fig. 2, falls back and opens the circuit of relay 211, at the same time preparing a new guard circuit for the trunk line. A moment later, relay 211 falls back and transfers conductor 208 from ground at its own contact to ground thru contacts of relay 212. In this way, the trunk line TL is guarded until it is again preselected in the manual office.

The entire connection is now released and the apparatus involved therein may be used

in setting up subsequent connections. When all cords are busy, all relays such as 301 are operated. Direct ground potential is then removed at all points from the common conductor 326, whereupon current through resistance 325 operates relay 609, Fig. 6, (and the similar relay in the other register set) provided the register set is not operating, in which case relays 610 and 612 are normal. Relay 609 prevents useless operation of the associated finder.

I claim:

1. In a telephone system, automatic trunk-selecting mechanism, trunk lines accessible thereto, each of said trunk lines being normally non-selectable to said switching mechanism, a plurality of digit registers, register connecting mechanism for connecting said registers to idle ones of said trunk lines, and means responsive to the connection of a register to a trunk line for rendering such trunk line selectable to said trunk selecting mechanism.

2. In a telephone system, automatic trunk selecting mechanism, trunk lines accessible thereto, each of said trunk lines being normally non-selectable to said mechanism, a plurality of digit registers, register connecting mechanism for connecting said registers to idle ones of said trunk lines, means responsive to the connection of a register to a trunk line for rendering such trunk line selectable to said trunk selecting mechanism, and distributing mechanism common to all said registers for governing the operation of said register connecting mechanisms so that such mechanism maintains each idle register connected with an idle trunk line.

3. In a telephone system, a plurality of groups of switching mechanism, a like plurality of groups of trunk lines accessible respectively to said groups, registers divided into as many groups as there are groups of said trunk lines, each of said trunk lines being normally non-selectable to the said switching mechanism having access to it, a trunk finder connected to each of said registers for finding and connecting the register with an idle trunk line, multiple connections between the banks of the said finders such that the finders corresponding to a given group of registers having access to trunk lines in the corresponding trunk group only, and means responsive to the effecting of a connection between a idle trunk line and a register sender by the finder associated with such register sender for rendering the connected trunk line selectable to the group of switching mechanism having access to said trunk line.

4. In a telephone system, an automatic office, a manual office, a group of trunk lines extending from said automatic office to said manual office, switching mechanism in said manual office for completing to manual lines terminating therein connections extending

from the automatic office to the manual office over said trunk line, call-indicating equipment including registers in said manual office for indicating to the manual operator the desired numbers, preselecting switching mechanism for effecting connections between said registers and idle ones of said trunk lines and for setting up a current-flow over each connected trunk line, automatic switching mechanism in the automatic office having access to said group of trunk lines, and means in said automatic office responsive to the current flow over a trunk line resulting from the connection of the register in the manual office thereto for rendering such trunk line selectable to said switching mechanism in the automatic office.

5. In a telephone system, an automatic office, a manual office, trunk lines extending from said automatic office to said manual office, call indicating equipment in the manual office for indicating to the operator thereat the destination of calls received over said trunk line, register senders in the automatic office for controlling the operation of said call indicating equipment, a group of local trunk lines in said automatic office corresponding to said manual office, automatic switching mechanism in said automatic office responsive to the portion of a number indicative of said manual office for extending a connection to one of said local trunk lines, means responsive to the remaining portion of the number for operating one of said register senders to record such remaining portion, secondary switching apparatus, and means effective only after the said remaining portion of a number has been completely registered for operating said secondary trunking apparatus to effect a connection between the seized local trunk line and an idle one of said automatic to manual trunk lines.

6. In a telephone system, a register sender, means for extending a connection thereto and for registering a plurality of digits in a telephone number, a distant register, means for extending a connection from said register sender to said distant register, said connection including two conductors, and means in said register sender for transmitting simultaneously to said distant register, two digits of equal length by transmitting impulses over said two conductors in series.

7. In a telephone system, a register sender, means for extending a connection thereto and for registering a plurality of digits in a telephone number, means for extending a connection from said register sender to a distant register, said connection including two conductors, means in said register sender for transmitting simultaneously to said distant registers, two digits of equal length by transmitting impulses over said two conductors in series, and means effective when the two digits are of unequal length for transmitting the

- extra portion of the longer digit over one conductor of the trunk line while effective impulses over the other conductor are prevented by a holding circuit including a separate return. 5
8. In combination, a sender and a distant register, two conductors extending from said sender to said register, a separate grounded receiving device in said register in series with each of said conductors, said conductors being conducted in series in said sender, a source of potential in series with said conductors for maintaining said receiving devices normally energized, and means for transmitting simultaneously impulses representing two digits over both conductors in series by interrupting said series circuit in said sender, and means effective when the two digits are of unequal length for establishing upon each 10 interruption a holding circuit over either of said conductors including a separate return for maintaining operated one of said repeating devices while the other is responding to the interruption. 15
9. In a telephone system, two offices, a trunk line extending from the first office to the second office, automatic switching mechanism in the first office having access to said trunk line, switching mechanism in the second office for completing a connection extended to said trunk line by said switching mechanism in the first office, means for releasing the connection in the first office prior to the release of the switching mechanism in the second office, and means in the first office, controlled over the two conductors of said trunk line in series and effective as long as the connection remains intact with the second office for rendering and maintaining said 20 trunk line busy to the switching mechanism in the first office. 25
10. In a telephone system, an automatic office and a manual office, a trunk line extending from said automatic office to said manual office, automatic switching mechanism in said automatic office for extending a connection to said trunk line, operator controlled mechanism in the manual office for extending a connection from said trunk line, means for interrupting the connection to the trunk line in the automatic office and for giving the operator in the manual office a disconnect signal, and means in the automatic office responsive to the interruption of the 30 connection in the automatic office and responsive to current flow over the two talking conductors of said trunk line in series for placing a guarding potential on said trunk line in the automatic office to prevent reseizure of said trunk line by the automatic switching mechanism, and means responsive to the breaking down of the connection in the manual office under the control of the operator for causing said means in the automatic office 35 to remove said guarding potential. 40
11. In a multi-office telephone system, a trunk selecting mechanism, an inter-office trunk line accessible but nonselectable at one end to said mechanism, means for extending a connection from the other end of said trunk line and for setting up a current flow over the trunk line, and means for thereupon rendering said trunk line selectable to said trunk selecting mechanism responsive to said current-flow. 70
12. In a multi-office telephone system, an inter-office trunk line, means at one end thereof for indicating that the trunk line is in a non-useable condition, means for linking an extension to the other end of the said trunk line and for applying a potential to a talking conductor thereof, and means for thereupon removing the non-useable indication from the said one end of the trunk line responsive to said application of potential. 75
13. In a multi-office telephone system wherein inter-office trunk lines are maintained unselectable at one office when they are not connected to receiving apparatus at the other office, means effective upon the connecting of a trunk line to receiving apparatus for setting up a current-flow over said trunk line, and means responsive thereto for removing the unselectable condition. 80
14. In a telephone system wherein trunk lines are maintained artificially busy at one end when they are not connected to receiving apparatus at the other end, means responsive to current-flow resulting from the connection of a trunk line to receiving apparatus for removing the busy condition, and a circuit including a talking conductor of said trunk line for controlling said means. 85
15. In a telephone system wherein trunk lines are indicated as unselectable at one end when they are not connected to receiving apparatus at the other end, means effective upon the connection of a trunk line with receiving apparatus for removing the unselectable indication, and a circuit including the two talking conductors of said trunk line in series for controlling said means. 90
16. In a telephone system, a telephone line, a sending device at one end of said line, a receiving device at the other end of said line, and means for operating said sending device to send two digits simultaneously over said line to said receiving device. 100
17. In a telephone system, a telephone line, a sending device at one end of said line, a receiving device at the other end of said line, and means for operating said sending device to send simultaneously two digits of the same telephone number over said line to said receiving device. 105
18. In a telephone system, a sending device, a receiving device, and means for operating said sending device in accordance with a telephone number to transmit two digits of 110
- 130

such telephone number simultaneously to said receiving device.

19. In a telephone system wherein impulses representing digits are transmitted incidental to the setting up of telephone connections, means for transmitting a single series of impulses indicative of a given digit and for registering such digit and another digit in response thereto.

19. 20. In a telephone system wherein impulses representing digits are transmitted incidental to the setting up of telephone connections, means for transmitting a series of impulses representing a digit of a given value and for registering such digit and a digit of a smaller value in response thereto.

21. In combination, means for transmitting a series of impulses, two registers, and means for operating one register to record one digit in response to such series and for operating another register simultaneously to record a digit of different value in response to such series.

22. In combination, two registers, means for generating a train of impulses, and means for setting one register responsive to only a predetermined portion of the impulses and for operating the other register in accordance with all of the impulses.

30. 23. In a telephone system wherein impulses are transmitted incidental to the setting up of telephone connections, means for transmitting a series of impulses representing a digit of given value, two registers, means for operating one of them in response to said impulses to register the transmitted digit and for operating the other one to register a digit of smaller value, and means for changing the character of the transmitted impulses as soon as the digit of smaller value is registered.

40. 24. In combination, an impulse transmitter, an impulse receiver, means for operating said transmitter to transmit a series of impulses, and a plurality of registering devices in said impulse receiver responsive to said series of impulses.

50. 25. In combination, an impulse transmitter, an impulse receiver, means for operating said impulse transmitter to transmit a group of impulses representing a digit and for transmitting a group of impulses representing an other digit, the second group being superimposed on the first said impulses so that all said impulses comprise a single series, and two registers in said receiving device responsive respectively to the said two groups of impulses.

60. 26. In a transmitting and receiving system arranged to transmit and receive digits of numbers by means of impulses, two registers, an impulse circuit extending between the transmitter and receiver, and means for sending impulses over said impulse circuit from the transmitter to the receiver to operate both of said registers during the same period

of time to register two digits of the same number.

27. In combination, an impulse receiver including a plurality of pairs of registers arranged to register a plurality of pairs of digits, respectively, a receiving circuit arranged to be associated with said pairs of registers successively, each of said pairs of registers being arranged and connected to operate from the receiving circuit to register a pair of digits, and means responsive to a pair of digits being received for transferring the association of the receiving circuit from the pair of registers with which it is associated to the next pair of registers.

28. In combination, two pairs of registers, a receiving circuit associated with the first pair, means responsive to impulses coming in over said receiving circuit for operating the first pair of registers, and means responsive to the cessation of said impulses for transferring the receiving circuit from the first pair of registers to the second pair of registers.

29. In combination, two pairs of registers and a receiving circuit, means responsive to impulses representing two digits received during the same period of time for operating the first pair of registers to record a pair of digits, and means responsive to the cessation of the impulses representing the longer of the two digits for transferring the receiving circuit to the next pair of registers.

30. In combination, registering apparatus, a sender, a plurality of groups of responding devices, a set of actuating conductors, means for setting said registering apparatus, means for controlling said sender in accordance with the setting of said registering apparatus to exercise a control over a plurality of said conductors, means for operating one of said groups of responding devices in accordance with the control exercised and for thereupon transferring said conductors to the next group of responding devices.

31. In combination, a register sender, a pair of actuating conductors, a plurality of storage sets, means for operating the sending apparatus of said register sender in accordance with the setting of the registering apparatus thereof to exercise a control over said pair of actuating conductors, one of said storage sets being responsive to the control to register the control exercised, and means effective upon the cessation of the control exercised over said pair of conductors for disassociating the conductors from the first storage set and for associating them with the second storage set.

32. In combination, registering apparatus arranged to register characters, a pair of conductors, a sender arranged to operate under control of said registering apparatus to send an impulse over one of said conductors and to send an impulse over the other of said

- conductors simultaneously, a pair of storage devices connected to said conductors, respectively, another pair of storage devices, the first pair of storage devices being responsive, respectively, to the impulses sent over said pair of conductors, and means effective upon the termination of the pair of impulses for thereupon transferring the pair of conductors to the next pair of storage devices.
- 5 33. In combination, registering apparatus operable to register a pair of digits, a pair of receiving devices, and a transmitter operable under the control of said registering apparatus to transmit two groups of impulses simultaneously to said receivers representing the registered digits, respectively. 75
- 10 34. In combination, registering apparatus arranged to register a pair of digits, and a sender operable under the control of said 20 registering apparatus to send two groups of impulses simultaneously corresponding, respectively, to the registered digits. 80
- 15 35. In combination, registering apparatus arranged to register a pair of digits, a 25 sender operable under the control of said registering apparatus to send two groups of impulses simultaneously corresponding, respectively, to the registered digits, and a pair of receiving devices arranged to receive the 30 two groups of impulses, respectively. 85
- 20 36. In combination, registering apparatus arranged to register a plurality of digits, and a sending device operable to send a plurality of groups of impulses simultaneously, 35 said groups of impulses being transmitted under the control of the registering apparatus and corresponding, respectively, to a group of registered digits, said sending device being operable subsequently to send a 40 second group of series of impulses corresponding, respectively, to digits recorded on said registering apparatus. 90
- 25 37. In combination, a plurality of separate registering devices, an impulse transmitter, 45 two conductors outgoing from said impulse transmitter, and means for operating said transmitter to send two groups of impulses simultaneously over said outgoing conductors, respectively, and under the control, respectively, of a pair of said registering devices. 95
- 30 38. In combination, a digit transmitter, a pair of outgoing conductors, and means for operating said transmitter to send impulses 55 over one of said conductors corresponding to a digit, and for operating said transmitter to simultaneously send impulses over the other outgoing conductor corresponding to a different digit. 105
- 35 39. A register transmitter comprising registering apparatus, a plurality of outgoing circuits over which digit impulses are transmitted, and a separate relay for each outgoing conductor, together with circuit arrangements for operating the said relays to 60 110
- 40 115
- 45 120
- 50 125
- 55 130
- 60 135
- 65 140
- control the number of impulses transmitted over the respective outgoing conductors.
- In witness whereof, I hereunto subscribe my name this sixth day of August, A. D., 1927.
- RUDOLPH F. STEHLIK. 70
